UNITED STATES PATENT OFFICE.

CASSIUS M. MILLER, OF CANTON, OHIO.

VALVE-GEAR FOR DUPLEX STEAM-PUMPS.

SPECIFICATION forming part of Letters Patent No. 399,203, dated March 5, 1889.

Application filed April 4, 1888. Serial No. 269,537. (No model.)

To all whom it may concern:

Be it known that I, CASSIUS M. MILLER, a citizen of the United States, and a resident of Canton, county of Stark, State of Ohio, have 5 invented a new and useful Improvement in Valve-Gear for Duplex Steam-Pumps, of which the following is a full, clear, and exact description, reference being had to the accompanying drawings, making part of this 10 specification.

My invention relates to an improvement in valve-gear for duplex steam-pumps; and it consists in providing means by which the piston of one engine may actuate the steam- 15 valve of the other, and for securing the parts in position and adjustment and for taking up lost motion caused by wear.

With these objects in view my invention consists of the hereinafter-described detail 20 and combination of parts, as set forth in the claims.

Figure 1 is a side elevation of a duplex steam-pump illustrating my invention. Fig. 2 is a vertical transverse section on a line 25 from z to z , and Fig. 3 is an isometrical view of a loop on the end of valve-stem, hereinafter explained.

Similar letters of reference indicate corresponding parts in all of the figures of the 30 drawings.

A represents one of a pair of twin steam-cylinders placed side by side, and, in this case, integral with the frame B and pump-cylinder C. The steam-cylinder and its ports are of 35 the usual form, having a centrally-located valve-seat on which is placed a slide-valve of the usual form and adapted to said seat, over which is placed the steam-chest D, said chest covering the valve-seat of both engines, and 40 having an overhung or inwardly-projected portion, E, as a support for the valve-rods F.

On the top of the main frame B is mounted a valve-gear-supporting frame, G, having threaded perforations a , in which is fitted 45 threaded pins b , having conical inner ends, as d . On the outer end of said pins is provided a transverse groove, as e , and a check-nut, f .

Rock-shafts H and J are provided, having 50 conical depressions h , corresponding with the conical ends of the pins b and centrally located in the ends of the said shafts, one being shown in each of the shafts. Shaft H is further

provided with an outwardly and downwardly projected arm, K, the lower end of which is adapted for engagement with a clip, L, secured to the piston-rod M, and a short depending finger, k , projected into and adapted to engage the ends $l m$ of a loop, N. Shaft J is also provided with an outwardly and downwardly projected arm, O, the lower end of which is adapted for engagement with a clip, L, secured to the piston-rod M', and an upwardly-projected finger, n , adapted for engagement with the ends $l m$ of a loop, N.

The shafts H J are placed between the vertical sides of the frame G and supported on the conical pins b , as shown, the pin having been turned in with an ordinary screw-driver set in the groove e . Said pins may be so turned in or out to carry the shaft into proper adjustment, and when so placed may be secured in such desired adjustment by the set-nuts f being turned onto the ends of the said pins and against the frame.

In this case it will be noticed that the lower 75 ends of the arms K and O are bifurcated, the prongs p and q embracing the clip L, and that the shafts H and J may be adjusted transversely to the piston-rod M M', so as to bring the arms K and O into a proper working alignment with the movement of the piston and clip L. An oil-duct, r , is provided in the rock-shafts H and J, connecting the depression h , and a perforation, s , by which oil may be conducted from the surface of the shaft to the 85 duct r , through which oil may be conducted to the conical depressions, and pins d , by which the parts may be lubricated.

The forward movement of the arm K by the piston M will move the valve to which it is geared in the same direction of the piston, the finger k pressing against the outer end of the loop N, while the outer movement of the arm O will move the valve to which it is geared in an opposite direction, and by this interchanging of the movement a continuous reciprocating movement of the steam valves and pistons is secured.

Having thus fully described the nature and object of my invention, what I claim, and desire to secure by Letters Patent, is—

1. The combination, with the piston-rods M M' and frame G, of the actuating-arms O K, rock-shafts H J, supported on adjustable coni-

cal pins *b*, fingers *k* *n*, loops *N*, and valve-stem support *E*, substantially as described, and for the purpose set forth.

2. The combination, with the frame *G*, of the 5 rock-shafts *H* and *J*, having oil-ducts *r* and *s*, conical depression *h*, pins *d*, and fingers *k* and *n*, substantially as described, and for the purpose set forth.

In testimony whereof I have hereunto set my hand this 24th day of March, A. D. 1888. to

CASSIUS M. MILLER.
